DESIGN FOR A COFFEE MILL

David A. Meeker and Franklin Douglass Houser,
Troy, Ohio, assignors to The Hobart Manufacturing Company, Troy, Ohio, a corporation of Ohio

Application August 13, 1937, Serial No. 71,070

Term of patent 14 years

To all whom it may concern:

Be it known that we, David A. Meeker and Franklin Douglass Houser, citizens of the United States of America, residing at Troy, in the county of Miami and State of Ohio, have invented a new, original, and ornamental Design for a Coffee Mill, of which the following is a specification, reference being had to the accompanying drawing, forming a part thereof, and in which

Fig. 1 is a perspective view of the coffee mill showing the new design;

Fig. 2 is a front elevational view on a smaller scale; and

Fig. 3 is a side elevational view of Fig. 2.

As shown, the design comprises a lower generally cylindrical casing, and an upper generally cylindrical storage hopper overhanging the lower casing.

We claim:

The ornamental design for a coffee mill substantially as shown and described.

DAVID A. MEEKER.
F. DOUGLASS Houser.
